COMBINED MOTOR AND HANDLE FOR AN ELECTRICALLY DRIVEN TOOL

Gyo Hirata, Tokyo, Japan

Application February 12, 1959, Serial No. 54,577

Term of patent 14 years

(Cl. D54—14)

FIG. 1

FIG. 2

FIG. 3

Fig. 1 is a side elevational view of a combined motor and handle for an electrically driven tool embodying my new design.

Fig. 2 is an end elevational view of the same taken from the left of Fig. 1.

Fig. 3 is an end elevational view taken from the right of Fig. 1.

I claim:

The ornamental design for a combined motor and handle for an electrically driven tool, as shown.
